INVENTOR.

Carl A. Heuler,

BY Chas. W. Gerard.

ATTORNEY.

UNITED STATES PATENT OFFICE

129,380

DESIGN FOR A BOTTLE CARRIER

Carl A. Heuler, Kansas City, Mo.

Application July 10, 1941, Serial No. 102,006

Term of patent 7 years

To all whom it may concern:

Be it known that I, Carl A. Heuler, a citizen of the United States, residing at Kansas City, county of Jackson, State of Missouri, have invented a new, original, and ornamental Design for a Bottle Carrier, of which the following is a specification, reference being had to the accompanying drawing, forming part thereof.

In the drawing, the figure shown represents a perspective view of a bottle carrier, showing my new design.

I claim:

The ornamental design for a bottle carrier, as shown.

CARL A. HEULER.
